**TILTABLE FORM FOR PRE-CAST
BUILDING UNITS**
George W. Sumner, 2300 Prater Way, No. 134,
Sparks, Nev.
Filed Sept. 10, 1962, Ser. No. 222,712
10 Claims. (Cl. 249—137)

This invention relates to a tiltable form for pre-cast units such as walls, panels, beams, columns, etc., of the type which are generally cast from concrete. This is a continuation-in-part application of my co-pending application Serial No. 759,620, filed September 8, 1958, now abandoned.

Prior to this invention the building industry erected structures using a pre-cast unit, such as a wall, by tilting the wall up from a horizontal to a vertical position with cranes. If the wall section was particularly large, it was cast in a horizontal position at the building site, usually on the floor of the building already laid. After the concrete in the wall had set, the wall was raised by attaching one or more cranes to one edge, and slowly raising the wall by that edge, the opposite edge of the wall serving as a fulcrum. The wall was then lifted and carried to the site where it was to be erected, and then lowered by the cranes into the proper position.

The disadvantage of the foregoing procedure is that heavy cranes or hoists and crews comprising several men must be used to move the units to the desired position, and the cast wall must ordinarily be thoroughly cured before it can be raised by the cranes, because of the relatively large stress placed on the wall in lifting it.

This invention provides a system for building with pre-cast units without the use of heavy cranes or hoists, making it possible for only one or two men to cast units and erect them in the desired location. Moreover, the invention substantially reduces the time normally required for curing the units before they can be lifted into position, because the molded units can be removed from their forms within a matter of a few hours, the actual time being controlled by the setting rate of the cement used.

In terms of apparatus for erecting a pre-cast structural unit, the invention contemplates a platform or table mounted on a support to tilt from a substantially horizontal position to an upright position. Means are included for mounting a unit on the platform when the platform is horizontal, and means are provided for tilting the platform and cast unit to an upright position after the unit has set. Means are provided for disengaging the unit from the platform so the unit can be left in an upright position.

In the preferred form of the invention, apparatus is arranged so the unit can be tilted to a vertical position above a foundation bearing, and means are provided for disengaging and slowly lowering the pre-cast unit from the platform onto the foundation bearing. Preferably, the unit is tilted about a horizontal axis passing substantially through its center of gravity so that a minimum amount of force is required to start the unit to tilt and restrain it from tilting once it has begun, and also so a minimum strain is imposed on the platform and unit during the tilting operation.

Preferably, a mold is mounted on top of the platform so the unit can be cast directly on the platform when in the horizontal position. For convenience of reference, the face of the platform which supports the mold is referred to as the front when the platform and mold are in the upright position. With the platform and mold in the horizontal position, those edges which become the top and bottom when the platform and mold are vertical are referred to as rear and front, respectively. The bottom edge of the mold, when the platform is tilted to the upright or vertical position, is movable with respect to the platform.

2

Support means are included to secure the upper edge of the unit, when tilted in the upright position, to the upper edge of the platform, and means are provided for moving the support means downwardly with respect to the platform so that the cast unit can be lowered when the platform is in the vertical position.

In the presently preferred form, a plurality of support means are attached to the cast unit at spaced locations, and means are provided for simultaneously lowering the support means so the cast unit is uniformly lowered through its horizontal extent.

In casting and erecting large units, say a wall 100 feet long and 24 feet high, the platform is preferably tilted by a plurality of longitudinally spaced hydraulic cylinders and pistons. The pistons are operated simultaneously so the entire platform and cast unit are raised uniformly into a vertical position. Preferably, means are provided for sensing the rate at which the cylinders are operated. If one portion of the unit tends to lead the rest during the elevating operation, the appropriate cylinder or cylinders are temporarily inactivated to bring all portions of the cast unit into desired alignment.

In handling relatively large units such as the wall just mentioned, it is often desirable to provide both longitudinal and lateral support to prevent the unit from sagging as it is lifted. For convenience of reference, the lateral direction is assumed to be parallel to the pivot axis of the platform, and the longitudinal direction is perpendicular to it. In one form of the invention, this result is achieved by suspending a longitudinal arch wire in tension from the rear to the front of the mold over the cast unit. The central portion of the arch wire rests on an upright stanchion which bears downwardly against the central portion of a cast unit to prevent longitudinal sagging. A similar result is achieved in the lateral direction by the use of a lateral arch wire secured at opposite ends to adjacent pistons under the mold. A jack or stanchion in the center portion of each lateral wire bears upwardly against the bottom of the platform between adjacent pistons, and restrains the cast unit from lateral sagging.

These and other aspects of the invention will be more fully understood from the following detailed description and the accompanying drawings in which:

FIG. 1 is a fragmentary side elevation showing the platform and a cast wall in a horizontal position;

FIG. 2 is a plan view taken on line 2—2 of FIG. 1;

FIG. 3 is a view taken on line 3—3 of FIG. 1;

FIG. 4 is a view of the rear of the platform in the vertical position;

FIG. 5 is a fragmentary elevation of the front of the platform and cast unit shown in FIG. 4;

FIG. 6 is a view taken on line 6—6 of FIG. 5;

FIG. 7 is a schematic diagram showing how the cylinders are synchronized to tilt the cast unit uniformly to an upright position; and

FIG. 8 is a fragmentary elevation similar to FIG. 5 and showing an alternate system for lowering the cast unit.

Referring to FIGS. 1, 2, and 3, an elongated rectangular scaffold or support 10 rests on the subfloor 12 of a building under construction. The platform is made up of a plurality of vertical stanchions 14 arranged in lateral and longitudinal rows and secured together by diagonal cross bars 16.

An elongated rectangular platform 20 rests on the upper ends of the stanchions of the support and is mounted by horizontal and laterally extending pivot pins 21 on the upper ends of stanchions in the front lateral row to pivot about a horizontal axis. As shown in FIG. 4, the platform is substantially the same width as the support, but is several times higher when tilted to the vertical position.

shown in FIG. 4. The platform is cantilevered a relatively short distance over the forward edge of the support by a distance approximately equal to the height of the support so that when the platform is tilted in a clockwise (as viewed in FIG. 1) direction, the lower edge 22 of the platform comes to rest a short distance above an elongated laterally extending foundation bearing 23.

One of the advantages in supporting the platform by horizontal pivot pins fairly close to the lower end of the platform is that the scaffolding and platform (when in the horizontal position) need not be more than a few feet above the ground when the concrete is poured. This is a considerable advantage in dumping concrete from conventional cement trucks.

As is shown best in FIGS. 3 and 4, the platform includes a plurality of longitudinal channel pieces 24 secured back to back at laterally spaced intervals. A plurality of lateral stringers 26, in the form of L-shaped bars, are secured at their opposite ends between adjacent longitudinal channel pieces 24. A flat board 28 is mounted on top of the platform and secured to the longitudinal and lateral members to form a smooth bottom of a mold 30 having side screed boards 32, a top screed board 35, and a bottom screed board 36. A concrete wall 37, or any other structure, is cast in conventional fashion within the mold. The top, bottom, and side screed boards are removably secured to the bottom of the mold by countersunk bolts 38 and nuts 40, as shown in FIG. 3, for the bottom screed board. A plurality of upwardly extending hydraulic cylinders 42 are secured at their respective lower ends by a laterally extending respective pivot pin 43 to a separate respective longitudinal brace 44. The opposite ends of each brace 44 are rigidly secured to the forward and rear bottom edges of the support to increase its rigidity and strength.

A strength set of telescoping pistons 48 is mounted in each cylinder, and the upper end of the smallest piston in each set is secured by a transverse pivot pin 50 to the central portion of a heavy frame 52, which extends a substantial distance longitudinally under the platform and is rigidly attached to it. Thus, the force exerted by each piston is distributed by its respective frame over a substantial area of the bottom of the platform. Each cylinder is supplied hydraulic fluid through a line 54 connected to a pump 56, which is powered by a motor 58 (FIG. 7).

A separate lateral arch wire 60 is secured at its opposite ends between adjacent frames 52. A separate jack 62 is mounted at the central portion of each arch wire to bear against the wire in the underside of channel members 24 in the platform. Thus, by suitably adjusting the jacks, the lateral arch wires are placed in tension to provide vertical support for the platform between the frames 52. This prevents the platform from tending to sag or develop waviness in the lateral direction, and still permits the platform to be of relatively light weight construction so it can easily be tilted with a minimum amount of equipment and power.

The platform and cast wall are prevented from sagging in the longitudinal direction by a plurality of laterally spaced and longitudinally extending support arch wires 64 secured at their opposite ends to anchors 66 mounted on the forward and rear edges of the platform. The central portion of each arch wire is supported by an upright stanchion 68 mounted on a laterally extending board 70 which rests on the cast wall. The desired tension in the longitudinal support arch wires is obtained by adjusting a respective turnbuckle 72 mounted in each wire. Each longitudinal arch wire extends through an eyebolt 74 mounted on the upper end of each of the support stanchions 68.

As shown in FIGS. 1, 4, and 7, a laterally extending sensing wire 76 is attached at its opposite ends to the sides of the bottom of the platform. The wire is attached to each control button 78 on switches 80 secured to the underside of the platform. As shown best in FIGS. 4 and

7, a separate switch 80 is mounted on a respective channel member adjacent each frame 52. Each switch controls the supply of electrical power from a conventional source 82 (FIG. 7) to a respective motor 58 for each pump 56. 5 A master switch 84 controls a supply of power to the individual switches 80, which are normally closed. When switch 84 is closed, the motors 58 are turned on to operate the pumps 52 to supply hydraulic fluid under pressure to each of the cylinders 42. The platform has some degree of flexibility as it is raised to the vertical position, and if one portion of its tends to move ahead of the rest, the wire 76 pulls the control button 78 of the appropriate switch, and the motor for the cylinder controlling that section is momentarily turned off until the section is again in line with the remainder of the platform.

As shown best in FIGS. 4 and 6, a plurality of threaded support rods 86 each extend through a conventional Saginaw screw 88 mounted on a bracket 89 secured to the upper (as viewed in FIG. 4) edge of the platform. Each Saginaw screw rests on a thrust bearing 90, and includes a conventional reversible ratchet mechanism 91, so that as a lever 92 is reciprocated, the threaded support rod 86 moves up or down, depending on the setting of the ratchet. The ratchet levers 92 are in pairs connected by a link 93. A motor 94 turns a crank 95, which drives a rod 96 connected between the crank and one of the ratchet levers 92. Thus, when each motor 94 is turned on, its crank is revolved to reciprocate the ratchet levers connected to it. The lower end of each support rod 86 is threaded into a respective fitting 97 welded to a horizontal pipe 98. A plurality of support cables 99 are looped over the pipe 98. The lower ends of each loop are secured to a swivel 100 which is attached to the upper end of a bolt 101 that extends down the top screed rail 35 and is threaded into a nut 102 imbedded in the concrete wall 37. Thus, the loops can be released from the wall by simply unscrewing the bolt 101 from the nut 102. A loop of anchor wire 104 is disposed around a reinforcing rod 106 in the wall. The ends of the anchor wire are welded to the nut 102. The bolts, nuts, loops, reinforcing rods, and horizontal pipe are installed at the time the wall is poured.

The operation of the device shown in FIGS. 1 through 7 is as follows. The cylinders and pistons are retracted so that the platform rests in a horizontal position on the support as shown in FIG. 1. In this condition, the cylinder and pistons extend upwardly and slightly rearwardly. The top, bottom, and side screed boards are fastened in position as shown in FIG. 1. Reinforcing rods are located as required within the mold, and any doors and windows that are to be formed in the wall are blocked out by conventional techniques. The lowering nuts 102 and bolts 101 are set in position as shown in FIG. 6. The anchor wires 104 are disposed around reinforcing rods 106 within the mold, and the ends of the wires 104 are welded to the nuts 102. The concrete is then poured into the top of the mold and worked flat. The lateral support arch wires 60 are secured under the platform as shown in FIG. 3 and placed under tension before the concrete is poured into the mold. This prevents lateral or transverse sagging or waviness in the wall.

As soon as the concrete takes an initial set, the support boards 70 are disposed across it, and the upright stanchions 68 are mounted as shown in FIG. 1 to hold the longitudinal support arch wires 64, which are placed in desired tension by the turnbuckles 72.

After the wall has set for 8 to 24 hours, and considerably sooner than it could be lifted by a crane without other support, it is tilted into a vertical position by closing switch 84 to turn on the pump motors that supply hydraulic fluid to the cylinders 42. Pistons 48 telescope outwardly from the cylinders, which swing slowly in a clockwise direction (as viewed in FIG. 1) about their respective pivot pins, and the wall is raised gently and uniformly to a vertical position over the foundation bear-

ing 23. If one section of the wall should tend to pull ahead of adjacent sections the appropriate switch 80 is actuated by the wire 76 to turn off the pump supplying fluid pressure to the cylinder in the section that is leading the rest of the wall. As soon as the rest of the wall catches up with the advanced section, that switch is again closed so that all sections advance together.

After the wall reaches the vertical position shown in FIGS. 4 and 6, the pumps are stopped, and the bottom and side screed rails are removed so that the wall is free to slide down the smooth bottom of the mold. The crank motors 94 are turned on, after the ratchets 91 have been set so that the support rods 86 are lowered as the cranks 95 turn.

After the bottom edge of the wall has come to rest on the foundation bearing 23, the cranks are stopped, and the wall is sealed to the foundation with grout and temporarily supported by braces (not shown) to permit the grout to set. If desired, a steel track 103 (FIG. 6), which may have been installed in the mold before the wall was cast, in the bottom edge of the wall comes to rest on plates 109 anchored in the foundation bearing and is welded to them before the application of grout.

The supporting loops at the upper edge of the wall are released by unscrewing the bolt 101, and the platform is now free to be pulled away from the wall and set up at the next site of operation.

FIG. 8 shows an alternate arrangement for lowering the cast wall from the top edge of the platform. The horizontal support pipe 98 is disposed through loops 99 removably secured to the top edge of the wall as shown in FIG. 6. The horizontal pipe is supported by a pair of support cables 110 attached at their lower ends to eyes 111 secured to the pipe. The upper portion of each cable is wound around a respective drum 112 mounted on the top edge of the platform to rotate on a shaft 113, which is parallel to the top edge of the platform and lies in the same plane as the platform. A motor 114 is mounted on the top edge of the platform, and supplies power to a gear box 115 which drives the shaft. To lower the wall, the motor is turned on to unwind the support cables from their respective drums and gently place the lower edge of the wall on the foundation bearings.

From the foregoing explanation, it will be apparent that the invention provides apparatus for quickly and easily setting a pre-cast unit such as a wall into place. Although the invention has been described with particular reference to a wall, it is also suitable for other units such as columns, beams, roofs, etc., in short, for almost any structural unit used in building.

With the invention, the pre-cast unit is tilted into place within a matter of hours after pouring, because the unit is supported by the platform as it is tilted so that there is a minimum amount of stress developed during the tilting operation. This is a marked improvement over prior practice when pre-cast units were picked up at one edge and tilted, using an opposite edge as a fulcrum. The large stresses imposed on the units by the prior practice required that they be cured to an advanced stage to insure having adequate strength to withstand the tilting operation, thereby increasing the time required between casting and tilting.

More important, the invention eliminates the need of heavy cranes or hoists to tilt a unit into place and thereby eliminates the cost of such equipment and the crew necessary for its operation. With the present invention, a wall can easily be cast and raised into place by two men, and if necessary, by one man. As far as is known, there is no limit to the size of the units that can be cast. Walls more than 100 feet in length and 24 feet high have been successfully cast and erected as described above.

I claim:

1. Apparatus for erecting a pre-cast unit from horizontal to an upright position on a foundation, the appa-

ratus including a scaffold disposed adjacent and above the foundation, a platform mounted on the scaffold over the foundation to tilt from a horizontal to an upright position, a mold for forming the pre-cast unit on top of the platform when in the horizontal position, the mold including a movable side which forms the bottom edge of the unit when in the upright position, means for tilting the platform from a horizontal to an upright position, support means disposed above said platform when in horizontal position and including portions extending through said mold and secured to the upper edge of the unit when tilted to the upright position for supporting the unit when tilted to the upright position, means fastening the support means to the upper edge of the platform in the upright position including means for lowering the upper edge of the unit downward with respect to the platform when tilted to the upright position, the lower edge of the unit being disposed over the foundation when first tilted to the upright position, and means for operating the lowering means of said fastening means to lower the support means relative to the platform until the lower edge of the unit rests on the foundation.

2. Apparatus for erecting a pre-cast unit from horizontal to an upright position on a foundation, the apparatus including a scaffold disposed adjacent and above the foundation, a platform mounted on the scaffold over the foundation to tilt from a horizontal to an upright position, a mold for forming the pre-cast unit on top of the platform when in the horizontal position, the mold including a movable side which forms the bottom edge of the unit when in the upright position, means for tilting the platform from a horizontal to an upright position, a first threaded member disposed above said platform when in horizontal position and including portions extending through said mold and secured to the upper edge of the unit when tilted to the upright position for supporting the unit when tilted to the upright position, a second threaded member engaged with the first threaded member and secured to the upper edge of the platform in the upright position to hold the first threaded member and permit it to be moved downwardly with respect to the platform when tilted to the upright position, the lower edge of the unit being disposed over the foundation when first tilted to the upright position, and means for rotating the two threaded members with respect to each other to lower the unit relative to the platform until the lower edge of the unit rests on the foundation.

3. Apparatus for erecting a pre-cast unit from horizontal to an upright position on a foundation, the apparatus including a scaffold disposed adjacent and above the foundation, a platform mounted on the scaffold over the foundation to tilt from a horizontal to an upright position, a mold for forming the pre-cast unit on top of the platform when in the horizontal position, the mold including a flat smooth bottom and a movable side which forms the bottom edge of the unit when in the upright position, means for tilting the platform from a horizontal to an upright position, support means disposed above said platform when in horizontal position and including portions extending through said mold and secured to the upper edge of the unit when tilted to the upright position for supporting the unit when tilted to the upright position, means fastening the support means to the upper edge of the platform in the upright position including means for lowering the upper edge of the unit downward with respect to the platform when tilted to the upright position, the lower edge of the unit being disposed over the foundation when first tilted to the upright position, and means for operating the lowering means of said fastening means to lower the support means relative to the platform until the lower edge of the unit rests on the foundation.

4. Apparatus for erecting a pre-cast unit from horizontal to an upright position on a foundation, the apparatus including a scaffold disposed adjacent and above the foundation, a platform mounted on the scaffold over

the foundation to tilt along a line adjacent one edge of the platform from a horizontal to an upright position, a mold for forming the pre-cast unit on top of the platform when in the horizontal position, the mold including a movable side which forms the bottom edge of the unit when in the upright position, means for tilting the platform from a horizontal to an upright position, support means disposed above said platform when in horizontal position and including portions extending through said mold and secured to the upper edge of the unit when tilted to the upright position for supporting the unit when tilted to the upright position, means fastening the support means to the upper edge of the platform in the upright position including means for lowering the upper edge of the unit downward with respect to the platform when tilted to the upright position, the lower edge of the unit being disposed over the foundation when first tilted to the upright position, and means for operating the lowering means of said fastening means to lower the support means relative to the platform until the lower edge of the unit rests on the foundation.

5. Apparatus for erecting a pre-cast unit from horizontal to an upright position on a foundation, the apparatus including a scaffold disposed adjacent and above the foundation, a platform mounted on the scaffold over the foundation to tilt from a horizontal to an upright position, a mold for forming the pre-cast unit on top of the platform when in the horizontal position, the mold including a movable side which forms the bottom edge of the unit when in the upright position, a cylinder and piston pivotally connected to the platform and scaffold for tilting the platform from a horizontal to an upright position, support means disposed above said platform when in horizontal position and including portions extending through said mold and secured to the upper edge of the unit when tilted to the upright position for supporting the unit when tilted to the upright position, means fastening the support means to the upper edge of the platform in the upright position including means for lowering the upper edge of the unit downward with respect to the platform when tilted to the upright position, the lower edge of the unit being disposed over the foundation when first tilted to the upright position, and means for operating the lowering means of said fastening means to lower the support means relative to the platform until the lower edge of the unit rests on the foundation.

6. Apparatus for erecting a pre-cast unit from horizontal to an upright position on a foundation, the apparatus including a scaffold disposed adjacent and above the foundation, a platform mounted on the scaffold over the foundation to tilt from a horizontal to an upright position, a mold for forming the pre-cast unit on top of the platform when in the horizontal position, the mold including a movable side which forms the bottom edge of the unit when in the upright position, a rigid frame attached to the bottom of the platform, a cylinder and piston pivotally attached between the frame and the scaffold for tilting the platform from a horizontal to an upright position, support means disposed above said platform when in horizontal position and including portions extending through said mold and secured to the upper edge of the unit when tilted to the upright position for supporting the unit when tilted to the upright position, means fastening the support means to the upper edge of the platform in the upright position including means for lowering the upper edge of the unit downward with respect to the platform when tilted to the upright position, the lower edge of the unit being disposed over the foundation when first tilted to the upright position, and means for operating the lowering means of said fastening means to lower the support means relative to the platform until the lower edge of the unit rests on the foundation.

7. Apparatus for erecting a pre-cast unit from horizontal to an upright position on a foundation, the apparatus including a scaffold disposed adjacent and above the

foundation, a platform mounted on the scaffold over the foundation to tilt from a horizontal to an upright position, a mold for forming the pre-cast unit on top of the platform when in the horizontal position, the mold including a movable side which forms the bottom edge of the unit when in the upright position, means for tilting the platform from a horizontal to an upright position, a plurality of spaced support means disposed above said platform when in horizontal position and including portions extending through said mold and secured to the upper edge of the unit when tilted to the upright position for supporting the unit when tilted to the upright position, separate means fastening each support means to the upper edge of the platform in the upright position including means for lowering the upper edge of the unit downward with respect to the platform when tilted to the upright position, the lower edge of the unit being disposed over the foundation when first tilted to the upright position, and means for simultaneously operating the lowering means of said separate fastening means to lower the support means relative to the platform until the lower edge of the unit rests on the foundation.

8. Apparatus for erecting a pre-cast unit from horizontal to an upright position on a foundation, the apparatus including a scaffold disposed adjacent and above the foundation, a platform mounted on the scaffold over the foundation to tilt from a horizontal to an upright position, a mold for forming the pre-cast unit on top of the platform when in the horizontal position, the mold including a movable side which forms the bottom edge of the unit when in the upright position, means for tilting the platform from a horizontal to an upright position, support means disposed above said platform when in horizontal position and including portions extending through said mold and secured to the upper edge of the unit when tilted to the upright position for supporting the unit when tilted to the upright position, means fastening the support means to the upper edge of the platform in the upright position including means for lowering the upper edge of the unit downward with respect to the platform when tilted to the upright position, the lower edge of the unit being disposed over the foundation when first tilted to the upright position, means for operating the lowering means of said fastening means to lower the support means relative to the platform until the lower edge of the unit rests on the foundation, an arch wire secured to the platform at spaced locations and disposed over the mold, and means disposed between the platform and an intermediate portion of the wire to bear against the wire and platform to place the wire in tension.

9. Apparatus for erecting a pre-cast unit from horizontal to an upright position on a foundation, the apparatus including a scaffold disposed adjacent and above the foundation, a platform mounted on the scaffold over the foundation to tilt from a horizontal to an upright position, a mold for forming the pre-cast unit on top of the platform when in the horizontal position, the mold including a movable side which forms the bottom edge of the unit when in the upright position, a plurality of spaced cylinders and pistons pivotally attached to the platform and scaffold for tilting the platform from a horizontal to an upright position, support means disposed above said platform when in horizontal position and including portions extending through said mold and secured to the upper edge 60 of the unit when tilted to the upright position for supporting the unit when tilted to the upright position, means fastening the support means to the upper edge of the platform in the upright position including means for lowering the upper edge of the unit downward with respect to the platform when tilted to the upright position, the lower edge of the unit being disposed over the foundation when first tilted to the upright position, means for operating the lowering means of said fastening means to lower the support means relative to the platform until the lower 75 edge of the unit rests on the foundation, a plurality of arch

wire sections, each section disposed under the platform and secured at its opposite ends to the platform adjacent the attachment of adjacent pistons to said platform and extending in the same general direction as the axis about which the platform pivots, and means disposed between the platform and wire to bear against the bottom of the platform and the wire between its ends.

10. Apparatus for erecting a pre-cast unit from horizontal to an upright position on a foundation, the apparatus including a scaffold disposed adjacent and above the foundation, a platform mounted on the scaffold over the foundation to tilt from a horizontal to an upright position, a mold for forming the pre-cast unit on top of the platform when in the horizontal position, the mold including a movable side which forms the bottom edge of the unit when in the upright position, a plurality of spaced means for tilting the platform from a horizontal to an upright position, means for separately actuating each of the tilting means, means for sensing the relative position of the tilting means, and means for independently deactuating at least one of the tilting means in response to its position to another tilting means, support means disposed above said platform when in horizontal position and including portions extending through said mold and secured to the upper edge of the unit when tilted to the upright position for supporting the unit when tilted to the upright position, means fastening the support means to the upper edge of the platform in the upright position including means for

lowering the upper edge of the unit downward with respect to the platform when tilted to the upright position, the lower edge of the unit being disposed over the foundation when first tilted to the upright position, and means for operating the lowering means of said fastening means to lower the support means relative to the platform until the lower edge of the unit rests on the foundation.
